BILL CLIP

Lloyd Bryan, Napa, Calif.

Application March 31, 1950, Serial No. 153,061

2 Claims. (Cl. 24—253)

1

The present invention relates to a novel and improved bill clip to hold paper money folded in such a manner as to be easily accessible and firmly held against disengagement.

The usual bill clip on the market today comprises a pair of arms flexibly connected together and adapted to be slipped over the folded bills to hold same in a compact package. The bills can be readily slipped out individually or as a package. This type of clip is objectionable in that there is no positive connection between the bill clip and the folded bills and the clip occasionally slips off the folded bills thereby affecting its usefulness. A further objection to this type of clip is that the clip becomes distorted when applied to a large number of bills and subsequent use on a small number of bills requires that the clip be bent back to its original shape.

A still further objection to the conventional type of clip is the fact that when carried in a pocket with other personal items, the clip may be accidentally separated from the folded bills during removal from the pocket. The conventional type of clip in order to be effective is of relatively large size thereby constituting a considerable surface bearing against the pocket of the user resulting in increased wear against the pocket material.

In its simplest form, the present invention contemplates a bill clip formed of three elements consisting of a pair of arms connected by a spring member. The spring member is equal to the width of the bills to be clipped and extends into the fold formed by the folded bills. Each of the arms overlap each other and due to the resiliency of the spring member, tend to press against each other. When assembled with a number of folded bills, the arms bear against opposite sides of the outermost folded bill. As a result of this construction, the clip is interconnected with the folded bills in such manner as to eliminate accidental separation of the clip and bills.

A further feature of the present invention resides in the provision of an improved clip construction wherein a portion of the clip is housed within the folded pack of bills thereby reducing the amount of clip material contacting the pocket surface without sacrificing the holding function of the clip.

Inasmuch as the clip is carried on the person at all times, it is well adaptable to identification plates, may have small compartments added for the safe carrying of small papers, such as a driver's license, or even have small collapsible knife blades, fingernail file and the like.

2

With the foregoing and other objects in view, the invention consists of the novel features of construction, combination and arrangement of parts to be hereinafter more fully illustrated, described and claimed.

In the drawing:

Figure 1 illustrates a perspective view of a preferred form of the invention.

Figure 2 illustrates a perspective view of the improved bill clip in association with a package of folded bills.

Figure 3 is a similar view showing a bill partly removed.

Figure 4 is a sectional view taken on the line 15 4—4 of Figure 2.

Figure 5 is a perspective view of a section of a modified form of bill clip.

Referring to Figure 1 showing a preferred embodiment of the invention, the clip comprises 20 three main elements designated by the letters A, B and C. Element A is an L-shaped member consisting of legs 10 and 11 formed of metal which may be of gold, silver or any suitable plated metal. It may be cast into the shape shown or 25 bent into form from flat stock. Leg 11 may be of any desired shape but should be of sufficient width to enable the surface to be inscribed with the name of the owner. Element B is similarly shaped and consists of legs 12 and 13. The two 30 elements A and B are oppositely disposed with legs 10 and 12 facing each other and legs 11 and 13 slightly overlapping. Element C comprises a coil spring 14 having its ends suitably secured as by welding or soldering to the lower inner 35 faces of legs 10 and 12. The coil spring 14 normally presses the two legs 11 and 13 towards each other but enables ready separation of the two legs.

The clip is assembled with the sheets or bills 40 15 as follows:

The sheets or bills 15 are initially stacked uniformly and slipped laterally between the legs 11 and 13 with the spring member 14 extending transversely of the stacked bills approximately 45 midway of the stack. At this point of the assembly, the clip straddles the stack of bills with leg 12 bearing against an edge of the stack as seen in Figures 2 and 3, leg 13 bearing against the outer surface of the outermost bill, and leg 11 and spring 14 bearing against the surface of the innermost bill. The stack is then folded about the spring and the folded half slipped between the leg 11 and the upper half of the innermost bill.

55 It will be apparent from the above that the

3

stack of bills will be held in compact form without any likelihood of the clip working loose from the stack. To remove a bill, one half of the bill can be slipped from under the leg 11 as seen in Figure 3 and then separated from the stack by a simple pull.

As previously pointed out, the present construction adapts itself to further uses and may have incorporated therewith numerous useful accessories. As seen in Figure 5, the same parts illustrated in Figure 1 are shown as elements 10', 13' and 14' with element 11' modified to form a pocket for a folding knife blade 16. The clip functions in the same manner as previously described with the additional advantage of an 15 easily carried pen knife.

While I have shown a preferred embodiment of the invention and a slight modification thereof, it will be readily apparent that further changes may be made in the construction of the 20 clip without departing from the inventive concept thereof. Accordingly, I do not wish to be limited precisely to the construction shown except as may be required by the scope of the following claims.

Having thus described the invention, what is claimed is:

1. A money clip for holding paper currency in a single fold condition comprising a torsion

5

4

spring member adapted to be received within the folded currency at the fold thereof, said spring member being of such length as to be co-extensive with the width of the paper currency, two parallel members adapted to lie along opposite edges of the folded currency, each parallel member being at right angles to the spring member and having its lower end secured to the respective end of the spring member, said parallel members having inwardly directed arms at their upper ends, each of said arms being of a length greater than one half of the length of the spring member and less than the full length of the spring member, said spring member being under such tension as to urge the arms into contact with each other.

2. A money clip as defined in claim 1, said torsion spring member being in the form of a coil spring.
